UNITED STATES PATENT OFFICE.

EDWARD C. MEIER, OF PHOENIXVILLE, PENNSYLVANIA.

FURNACE-TILE.

1,167,510.

Specification of Letters Patent.

Patented Jan. 11, 1916.

Original application filed August 14, 1915, Serial No. 45,551. Divided and this application filed October 11, 1915. Serial No. 55,225.

To all whom it may concern:

Be it known that I, EDWARD C. MEIER, a citizen of the United States, residing at Phoenixville, in the county of Chester and 5 State of Pennsylvania, have invented certain new and useful Improvements in Furnace-Tiles, of which the following is a specification.

My invention relates to improvements in 10 furnace tile, and more particularly to an improved cast iron tile having an inclined groove therein adapted to direct the steam from a soot blower inserted through a stay tube in the box header into the groove 15 formed in the baffling tile supported on the boiler tube.

In the arrangement of baffling tile on 20 boiler tubes, it frequently happens that such tile are so disposed that a soot blower directed through a stay tube will be out of alignment with the upper or grooved face of the tile, and in such case my improved metal tile is used and operates as a deflector or inclined trough to properly direct the 25 steam into the groove of the baffling tile.

A further object is to provide a metal tile which is especially adapted for use in connection with my improved grooved baffling tile, and which is so arranged that the inclined groove in the metal tile registers with the groove in the baffling tile, and insures a proper direction of the steam for blowing out the soot.

This is a division of my application for 35 patent on furnace tile, filed August 14, 1915, and given Serial No. 45,551.

With these and other objects in view, the invention consists in certain novel features of construction and combinations and arrangements of parts as will be more fully 40 hereinafter described and pointed out in the claims.

In the accompanying drawings: Figure 1 is a fragmentary view in vertical longitudinal section illustrating my improvements. 45 Fig. 2 is a fragmentary view in section on the line 2—2 of Fig. 1, my improved metal tile being shown in end elevation. Fig. 3 is an enlarged fragmentary plan view showing 50 the box header and stay tube in section, and the other parts in elevation.

1 represents a steam drum of the boiler which communicates and is supported by a box header 2, the latter communicating

with boiler tubes 3, and provided with stay 55 tubes 10.

The construction above described is a common type of boiler, and I would have it understood that my present invention is not limited to any particular construction of 60 boiler, and may be used with various types.

On the boiler tubes 3, baffling tile 4 are supported, and these baffling tile are preferably of burnt fire brick or clay, and are provided in their upper faces with longitudinal grooves 5 constituting a repository for soot which accumulates therein. These tile 4 I term "baffling tile" to distinguish them from my improved metal tile 6, although the latter operates as a baffling tile. This 70 tile 6, as above stated, is preferably of cast iron, and is provided at its sides with curved faces 7, which rest against and are supported by the boiler tubes 3. The tile 6 inclines upwardly from its outer to its 75 inner end, and is of general trough shape throughout, the upper end of the tile 6 registering with the grooved surface 5 of tile 4, while the lower end of the tile 6 is located in a plane below the stay tube 10 80 through which the soot blower (not shown) directs the steam to blow out the soot which is deposited in the groove 5 of the tile. The stay tube 10 is up-set or flared outwardly at its ends as shown at 8, and the tile 6 at one 85 end is recessed as shown at 9 to accommodate the end 8 of tube 10 and allow the tile 6 to lie snugly against the header 2.

With my improvements it will be noted that when the blower is directed through the 90 tube 10, the steam will be directed through the tile 6 into the groove 5 of tile 4, and it will also be noted that the tile 6 has its groove 11 widest at its end adjacent the tube 10 and gradually decreases in width to its 95 other end where it conforms in width to the width of the groove 5, so that the tile 6 not only tapers upwardly from one end to the other, but its groove or trough 11 decreases in width from its inlet to its outlet end, 100 hence the steam is more or less confined, and the tile operates to a certain extent as a nozzle to direct the steam through the groove 5.

Various slight changes might be made in 105 the general form and arrangement of parts described without departing from my invention, and hence I do not limit myself to

the precise details set forth, but consider myself at liberty to make such changes and alterations as fairly fall within the spirit and scope of the appended claims.

5 Having thus described my invention, what I claim as new and desire to secure by Letters Patent is:

1. A tile, comprising a steam guide adapted to be located at the end of a series of 10 baffling tile and having a groove in its upper face forming a steam passage widest at its inlet end and diminishing in width to its outlet end, substantially as described.

2. A tile, comprising a steam guide adapt-

ed to be located at the end of a series of 15 baffling tile and having a groove in its upper face forming a steam passage widest and deepest at its inlet end and diminishing in width and depth to its outlet end, substantially as described.

20

In testimony whereof I have signed my name to this specification in the presence of two subscribing witnesses.

EDWARD C. MEIER.
